To all whom it may concern:

Be it known that I, Louis Postman, a citizen of the United States of America, residing in Manhattan, county of New York, and State of New York, have invented a new, original, and ornamental Design for a Glove, of which the following is a specification, reference being had to the accompanying drawing, forming part thereof.

Fig. 1 is a front view of a glove, showing my new design.

The characteristic feature of the design resides in the continuation of the stitching from the top of the glove, around the overlap and down the centre of the back.

I claim:

The ornamental design for a glove, substantially as shown and described.

LOUIS POSTMAN.
